PATTERN SELECTING MECHANISM

George Herbert White, Hartford, Conn., assignor,
by mesne assignments, to Macomic Corporation,
a corporation of Delaware

Application December 30, 1932, Serial No. 649,573

19 Claims. (Cl. 276—12)

My invention relates to improvements in pattern selecting mechanism and has for one object to provide a connection between a standard typewriter and a plurality of rockable pattern selecting shutters or plates such as may be used in connection with a type casting or type selecting mechanism.

One of the objects of this invention is to provide a light, durable, convenient and accurate connecting apparatus to transmit power from the typewriter to the shutter bed. Another object is to provide a convenient smoothly operating and accurate connection between the typewriter and elements controlled by it so that the typewriter may be replaced or renewed and the device assembled and disassembled without derangement of the essential operating parts. Other objects of the invention will appear from time to time throughout the specification and claims.

20 My invention is illustrated more or less diagrammatically throughout the accompanying drawings, wherein—

Figure 1 is a diagrammatic side elevation in part section;

25 Figure 2 is a detail front elevation of the device shown in Figure 1 with parts broken away;

Figure 3 is a section along the line 3—3 of Figure 1;

Figure 4 is an enlarged section along the line 30 4—4 of Figure 1;

Figure 5 is a diagrammatic side elevation of the frame structure at a reduced scale;

Figure 6 is a partial sectional view similar to Figure 1 with parts in different positions.

35 Like parts are indicated by like characters throughout the specification and drawings.

It will be understood that the apparatus which forms the basis for this application is merely one of the elements in a complicated pattern selecting mechanism adapted for use in connection with type casting and type setting machines but owing to the complication of the device and the large number of parts involved, I have illustrated in this case only those parts of the mechanism 40 which form the subject matter of this present invention showing them in their proper setting but not illustrating in detail the remaining parts.

45 It will be understood that the mechanism I am dealing with is a complete operating unit in itself but serves as one unit in a chain of mechanisms. I have illustrated it as part of a type casing machine though obviously the selecting mechanism might be used in connection with type setting machines or in other machines where it 50 was desired to select certain elements, form a pat-

tern, or to designate certain specific parts or cause certain specific elements to move or to remain at rest.

The machine, of course, comprises a rigid framework A A¹, uprights A² A³, a lower cross member A⁴ and an upper cross member A⁵. Joining the upper and lower cross members A⁴, A⁵ and supported on them is a typewriter and shutter bed A⁶ which in working position is inclined to the horizontal as indicated. Projecting above this bed, preferably mounted on it and preferably integral with it is a generally horizontal typewriter platform A⁷. The typewriter bed has at either side downwardly extended flanges A⁸ upon which the shutters are pivoted and which flanges 10 form with the typewriter bed the shutter bed and also form in effect a closure or housing for the selecting mechanism.

15 B is a typewriter having a plurality of key levers B¹ mounted for rotation about a pivot axis B² and adapted to be guided in their vertical movement by a key bar comb plate B³. Extending across beneath the typewriter key bars, mounted on the typewriter platform A⁷ is a comb plate B⁴. Projecting upwardly through the comb plate are a plurality of plungers, push rods or typewriter key extensions B⁵, there being one in register with each key bar B¹. These push rods B⁵ are pivoted on relatively flat bell crank levers B⁶ which are pivoted in the typewriter platform. 20 Spring B⁷ holds the push rods seated in the comb plate B⁴ tending to rotate them forwardly toward the operator. These push rods are free to move 25 up and down in the comb plate being positioned in the comb plate by the spring B⁷ and by their pivotal relation with the levers B⁶ so that when the operator pushes down on the key, the lever descends, engages the push rod and causes the bell crank lever B⁸ to rotate in a counterclockwise direction as shown in Figure 6. The inner 30 ends of the levers B⁶ are provided with a plurality of holes B⁹ spaced along the axis of the lever. Diagonal pull rods B¹⁰ extend downwardly from one of these holes B⁹ in engagement with a bell crank lever B¹¹ pivoted on the shutter bed, 35 holes B¹¹ being engaged by the opposed ends of the pull rods B¹⁰ so that the plurality of holes in the levers B⁶ and B¹¹ give a relatively wide range of adjustment between the two levers.

Pivoted on the flanges A⁸ are a series of selecting shutters. These shutters comprise channels C, each channel having welded or otherwise attached to the outer central portion thereof of adjacent one side pivot arms C¹ which are offset from the axis of the shutter and termi- 50 55

nate in pin bearing extensions C². These pin bearing extensions are engaged by pivot pins C³ in the flanges A⁸ so that each shutter is free to rock about an axis removed from the body thereof. The shutter channel is relatively wide and has two flanges, one wider than the other, the shorter one having a very gradual curvature so as to provide a curved contact face. Welded or otherwise attached to each shutter at some point between its ends is a shutter arm C⁴, it being understood that since there are a plurality of these shutters, the shutter arms for successive shutters are spaced along the shutter so as to be generally in line with the mechanism controlling that individual shutter. C⁵ is a tension rod between a perforation on the shutter arm and the free end of one of the bell crank levers B¹⁰. C⁶ is a resistance spring provided for the purpose of resisting rotation of the shutter in a counterclockwise direction as shown in Figure 1 under the influence of the typewriter key and for returning the shutter to the starting position after the key has caused its rotation. It will be understood that there is one shutter for each typewriter key, that the connecting mechanism between such typewriter key and the shutter is all in one generally vertical plane so that there is interposed between each shutter the series of pull bars, bell crank levers and push rods whereby depression of any typewriter key may cause a rotation of the associated shutter. It will be understood, of course, that the pull rods C⁵ are of varying length because the bell crank levers B¹⁰ are on the same axis and the shutters are spaced along the shutter bed, hence a longer or shorter member C⁵ is needed to connect each bell crank lever B¹⁰ with its associated shutter. The spring C⁶ comprises any suitable type of tension spring. It is anchored at one end on the 40 shutter lever C⁴ and at the other end on an anchorage frame C⁷. This frame is mounted on the shutter bed above the plane of the shutters. This anchorage frame has one or more cross members which serve as one abutment or anchorage for the tension rod resistance spring combination C⁵ C⁶.

The operator treats the typewriter in the usual customary manner. When he or she strikes the typewriter key the key bar moves down, engages the end of the push bar or plunger and moves it down. The spring holds the plunger in proper position in the guide comb and since the lower end of the plunger is pivoted on the end of the flat bell crank lever, that lever rotates (referring to Figure 1) in a counterclockwise direction exerting a tension on the angular bell crank lever associated with the shutter bed and rotating it in a clockwise direction. This in turn rocks the shutter against the resistance of the spring and wire combination anchored on the abutment or anchorage frame so that every key in the typewriter controls the operation as it comes down of one of the shutters in the shutter bed.

The further links in the chain as above indicated, namely, the parts actuated by the rotation of the shutter, since they form no part of the invention herein claimed have been omitted.

It will be noted that the shutters extend clear across the width of the typewriter. The typewriter keys are distributed clear across the width of the typewriter bed but the combination of typewriter key, plunger, two bell cranks, connecting rods and the lever on the shutter are so arranged as all to be in the same general vertical plane located by the typewriter key bar. It

will be realized that whereas I have described and shown a practical and operative device, nevertheless many changes may be made in size, shape, number and disposition of parts without departing from the spirit of my invention. I wish my description and drawings, therefore, to be taken as in a broad sense illustrative or diagrammatic rather than as limiting me to the precise structure herein shown. It will be realized, for example, that my invention is applicable not merely to type casting mechanisms but to mechanisms where type is selected for other purposes than for casting. Therefore, where in the claims I use the words "for type casting machines and the like" I wish this term to be interpreted with sufficient latitude to include machines where type is selected for other purposes than for casting.

I claim:

1. A pattern forming mechanism for type casting machines and the like comprising an inclined supporting bed, a plurality of pivoted pattern selecting shutters arranged side by side thereon, a horizontal platform associated with the bed, a standard typewriter mounted thereon and a working connection between each shutter and a key of the typewriter whereby depression thereof causes rotation of the shutter.

2. A pattern forming mechanism for type casting machines and the like comprising an inclined supporting bed, a plurality of pivoted pattern selecting shutters arranged side by side thereon, a horizontal platform associated with the bed, a standard typewriter mounted thereon and a working connection between each shutter and a key of the typewriter whereby depression thereof causes rotation of the shutter, the connection being adjustable whereby the shutter excursion may be adjustable in relation to the typewriter key movement.

3. A pattern forming mechanism for type casting machines and the like comprising an inclined supporting bed, a plurality of pivoted pattern selecting shutters arranged side by side thereon, a horizontal platform associated with the bed, a standard typewriter mounted thereon and a working connection between each shutter and a key of the typewriter whereby depression thereof causes rotation of the shutter, the working connection comprising a pair of levers, a connection between the two levers and a connection between one lever of the pair and the shutter and between the other lever of the pair and the key.

4. A pattern forming mechanism for type casting machines and the like comprising an inclined supporting bed, a plurality of pivoted pattern selecting shutters arranged side by side thereon, a horizontal platform associated with the bed, a standard typewriter mounted thereon and a working connection between each shutter and a key of the typewriter whereby depression thereof causes rotation of the shutter, the working connection comprising a pair of levers, a connection between the two levers and a connection between one lever of the pair and the shutter and between the other lever of the pair and the key, the connection between the levers comprising a rod pivoted on each lever, the opposed lever arms having a plurality of holes whose distance from the pivot varies whereby the relation between them may be adjustable.

5. A pattern forming mechanism for type casting machines and the like comprising an inclined supporting bed, a plurality of pivoted pattern selecting shutters arranged side by side thereon, a horizontal platform associated with the bed, a

- standard typewriter mounted thereon and a working connection between each shutter and a key of the typewriter whereby depression thereof causes rotation of the shutter, the working connection comprising a pair of levers, a connection between the two levers and a connection between one lever of the pair and the shutter and between the other lever of the pair and the key, said connections being relatively inclined one to another. 5
6. A pattern forming mechanism for type casting machines and the like comprising an inclined supporting bed, a plurality of pivoted pattern selecting shutters arranged side by side thereon, a horizontal platform associated with the bed, a standard typewriter mounted thereon and a working connection between each shutter and a key of the typewriter whereby depression thereof causes rotation of the shutter, the working connection including a lever, a plunger pivotally supported thereon at one end and associated at the other end with the typewriter key and guide means adapted to maintain the plunger in working relation with the key irrespective of key and lever movement. 10
- 20
- 25
7. A pattern forming mechanism for type casting machines and the like comprising an inclined supporting bed, a plurality of pivoted pattern selecting shutters arranged side by side thereon, a horizontal platform associated with the bed, a standard typewriter mounted thereon and a working connection between each shutter and a key of the typewriter whereby depression thereof causes rotation of the shutter, the working connection including a lever, a plunger pivotally supported thereon at one end and associated at the other end with the typewriter key and guide means adapted to maintain the plunger in working relation with the key irrespective of key and lever movement, said guide means comprising a slotted member through which the plunger is free to reciprocate and yielding means adapted to hold the plunger seated in the slot. 30
- 40
- 45
8. A pattern forming mechanism for type casting machines and the like comprising an inclined supporting bed, a plurality of pivoted pattern selecting shutters arranged side by side thereon, a horizontal platform associated with the bed, a standard typewriter mounted thereon and a working connection between each shutter and a key of the typewriter whereby depression thereof causes rotation of the shutter, the connection including a bell crank lever adjacent the supporting bed, a connection between one arm thereof and the shutter and a connection between the other arm of the lever inclined to the first mentioned connection and extending toward the typewriter. 50
- 55
- 50
9. A pattern forming mechanism for type casting machines and the like comprising an inclined supporting bed, a plurality of pivoted pattern selecting shutters arranged side by side thereon, a horizontal platform associated with the bed, a standard typewriter mounted thereon and a working connection between each shutter and a key of the typewriter whereby depression thereof causes rotation of the shutter, yielding means adapted to resist the movement of the shutter in response to depression of the typewriter key, a lever rigidly mounted on the shutter upon which the yielding means and the operating connection both act, the lever arms through which they act being unequal. 60
- 65
- 70
- 75
10. A pattern forming mechanism for type casting machines and the like comprising an inclined supporting bed, a plurality of pivoted pattern selecting shutters arranged side by side thereon, a horizontal platform associated with the bed, a standard typewriter mounted thereon and a working connection between each shutter and a key of the typewriter whereby depression thereof causes rotation of the shutter, yielding means including a fixed abutment and a tension wire and spring interposed between the abutment and shutter for resisting movement of the shutter in response to depression of the typewriter key, a lever rigidly mounted on the shutter upon which the yielding means and the operating connection both act, the lever arms through which they act being unequal. 5

15. A pattern forming mechanism for type casting machines and the like comprising a supporting bed, a plurality of pivoted pattern selecting shutters arranged side by side thereon, a standard typewriter associated therewith and a working connection between each shutter and a key of the typewriter whereby depression of the key causes rotation of the shutter, such connection comprising a pair of levers, a connection between the two levers, a connection between one lever of the pair and the shutter, a connection between the other lever of the pair and the key, the connection between the levers comprising a 70
- 75

rod pivoted on each lever, the opposed lever arms having a plurality of holes whose distance varies whereby the relation between them is adjustable.

16. A pattern forming mechanism for type casting machines and the like comprising a supporting bed, a plurality of pivoted pattern selecting shutters arranged side by side thereon, a standard typewriter associated therewith and a working connection between each shutter and a key of the typewriter whereby depression thereof causes rotation of the shutter, such connection including a lever, a plunger pivotally supported thereon at one end and associated at the other end with the typewriter key and guide means adapted to maintain the plunger in working relation with the key irrespective of key and lever movement.

17. A pattern forming mechanism for type casting machines and the like comprising a supporting bed, a plurality of pivoted pattern selecting shutters arranged side by side thereon, a standard typewriter associated therewith and a working connection between each shutter and a key of the typewriter whereby depression thereof causes rotation of the shutter, such connection including a lever, a plunger pivotally supported thereon at one end and associated at the other end with the typewriter key and guide means adapted to maintain the plunger in working relation with the key irrespective of key and lever movement, said guide means comprising a slotted member through which the plunger is free to reciprocate and yielding means adapted to hold the plunger in the slot.

18. A pattern forming mechanism for type casting machines and the like comprising a supporting bed, a plurality of pivoted pattern selecting shutters arranged side by side thereon, a standard typewriter associated therewith and a working connection between each shutter and a key of the typewriter whereby depression of the key causes rotation of the shutter, yielding means adapted to resist the movement of the shutter in response to a depression of the typewriter key and a lever rigidly mounted on the shutter, the yielding means and the operative connection being both adapted to work on said lever, the lever arms through which they act being unequal.

19. A pattern forming mechanism for type casting machines and the like comprising a supporting bed, a plurality of pattern selecting shutters arranged side by side thereon, a standard typewriter associated therewith and a working connection between each shutter and a key of the typewriter whereby depression of the key causes rotation of the shutter, yielding means including a fixed abutment and a tension wire and spring interposed between the abutment and the shutter for resisting movement of the shutter responsive to depression of the typewriter key, the abutment comprising a frame having a plurality of diagonal members extending across the supporting bed in a plane adjacent it and parallel with the plane of the shutters.

GEORGE HERBERT WHITE.
